UNITED STATES PATENT OFFICE.

THOMAS F. FREEMAN, OF DOVER, MAINE.

SEAM-RIPPER.

No. 914,130.

Specification of Letters Patent. Patented March 2, 1909.

Application filed June 10, 1908. Serial No. 437,715.

To all whom it may concern:

Be it known that I, THOMAS F. FREEMAN, a subject of the King of Great Britain, and a resident of Dover, in the county of Piscataquis and State of Maine, have invented a new and Improved Seam-Ripper, of which the following is a full, clear, and exact description.

This invention relates to seam rippers and 10 more particularly such as combine a lap-board and a cutter, and are adapted to be used for the opening of letters, wrappers, seams of garments, and the like.

The object of the invention is to provide a 15 device of the class described, simple in construction and inexpensive to manufacture, and adapted to be adjusted across the lap of the user, so that the cutter will be in a convenient position for use, thus leaving both 20 hands of the operator free.

The invention consists in the construction and combination of parts to be more fully described hereinafter and particularly set forth in the claims.

25 Reference is to be had to the accompanying drawings forming a part of this specification, in which similar characters of reference indicate corresponding parts in all the views.

Figure 1 is a perspective view of an embodiment of the invention showing the same 30 in position for use; Fig. 2 is a front elevation of the same, showing, in dotted outline, the hinged ends folded into an inoperative position; Fig. 3 is a cross section on the line 3—3 35 of Fig. 2; and Fig. 4 is a perspective view of a modification of the invention.

Referring more particularly to the drawings, I provide a seam ripper having a lap-board or frame 1. The latter has downwardly curved and inwardly disposed ends 2 40 adapted to rest against the thighs of the operator to hold the device in position. The ends 2 and the lap-board have extensions 3 with registering openings 4, through which hinge pins 5 are passed. As shown most 45 clearly in Fig. 2, these hinged ends may be folded against the under part of the lap-board in an inoperative position.

Located at the center of the lap-board is a cutter 6 of any desired form, and having a 50 knife edge 7. The cutter has a threaded shank 8 which is removably arranged in an opening 9 in the lap-board, a nut 10 being used to hold the cutter in position.

It should be understood that any desired 55 form of cutter may be used, according to the character of the work to be performed.

When in use, the device is held in position by the outward pressure of the thighs against the curved ends, which are formed to fit 60 snugly against the same.

As shown in Fig. 4, the device may be constructed to have a wire frame body, the ends of which are suitably bent to rest against the thighs of the operator. In this form, a cross 65 member 11 is used to mount the cutter 6.

Having thus described my invention, I claim as new and desire to secure by Letters Patent:—

1. A seam ripper comprising a supporting 70 body having hinged ends adapted to engage against the thighs of an operator, and a cutter removably arranged on said body said ends being foldable against said body into inoperative position. 75

2. A seam ripper comprising a supporting body having downwardly and inwardly disposed ends adapted to rest against the thighs of an operator to hold the body in position, and a cutter removably arranged upon said 80 body.

3. A seam ripper comprising a supporting body adapted to be arranged across the legs of an operator, and having foldable ends suitably curved so that they will engage the 85 thighs of the operator to hold the body in position, and a cutter removably arranged upon said body.

In testimony whereof I have signed my name to this specification in the presence of 90 two subscribing witnesses.

THOMAS F. FREEMAN.
